Primary Examiner — Robert M Spear*Assistant Examiner* — Darcey E Heflin(74) *Attorney, Agent, or Firm* — Stephen J. Weyer, Esq.; Stites & Harbison, PLLC.(57) **CLAIM**

The ornamental design for a sealing ring for a bottle, as shown and described.

DESCRIPTION

This relates to the subject matter in co-filed U.S. Design patent applications Ser. Nos. 29/491,585; 29/491,589; and 29/491,591, filed on May 22, 2014, all herein incorporated by reference.

FIG. 1 is a perspective view taken from the top, front, and right side of the sealing ring for a bottle of the present design.

FIG. 2 is a front elevation view of the sealing ring for a bottle of FIG. 1.

FIG. 3 is a rear elevation view of the sealing ring for a bottle of FIG. 1.

FIG. 4 is a right side elevation view of the sealing ring for a bottle of FIG. 1, the opposite side being a mirror image thereof; and,

FIG. 5 is a top plan view of the sealing ring for a bottle of FIG. 1, the bottom rear view being a mirror image thereof. Portions drawn in broken lines in FIGS. 1 and 5 form no part of the claimed design.
